UNITED STATES PATENT OFFICE

106,110

DESIGN FOR A COMBINED BAG AND CLOSURE

John A. Farmer, Lancaster, Pa.

Application September 26, 1935, Serial No. 58,733

Term of patent 14 years

To all whom it may concern:

Be it known that I, John A. Farmer, a citizen of the United States, residing at Lancaster, in the county of Lancaster and State of Pennsylvania, have invented a new, original, and ornamental Design for a Combined Bag and Closure, of which the following is a specification, reference being had to the accompanying drawing, forming part thereof.

Fig. 1 is a side elevational view of a combined bag and closure showing my new design;

Fig. 2 is an edge elevation thereof; and
Fig. 3 is a perspective view of the same.

The dominant and characteristic feature of my new design consists in the closure tab or sealing member of sheet material, substantially of the configuration shown in full lines as applied to the mouth of the bag.

I claim:

The ornamental design for a combined bag and closure, substantially as shown and described.

JOHN A. FARMER.
